(57) **CLAIM**

The ornamental design for a integrated actuator, as shown and described.

DESCRIPTION

FIG. 1 is a front perspective view of my integrated actuator;
FIG. 2 is a top view thereof;
FIG. 3 is a bottom view thereof;
FIG. 4 is a left side elevation view thereof;
FIG. 5 is a right view thereof;
FIG. 6 is a front view thereof; and,
FIG. 7 is a back view thereof.
My integrated actuator is characterized by its unique shape shown FIGS. 1 through 7.
